G. IVALDI

TOOL HOLDER

Filed April 20, 1923

WITNESS

Wm. Bell.

INVENTOR

Giuseppe Ivaldi,
BY
John S. Senn, ATTORNEY

UNITED STATES PATENT OFFICE.

GIUSEPPE IVALDI, OF PATERSON, NEW JERSEY.

TOOL HOLDER.

Application filed April 20, 1923. Serial No. 633,459.

To all whom it may concern:

Be it known that I, GIUSEPPE IVALDI, a subject of the King of Italy, residing at Paterson, in the county of Passaic and State 5 of New Jersey, have invented certain new and useful Improvements in Tool Holders, of which the following is a specification.

This invention relates to holders in which rotary tools, such as drills, are held. In 10 the ordinary construction of such a holder a hole is provided transverse to the tool socket thereof so that a drift can be introduced for driving out the tool. This drift in time burrs the end of the tool shank 15 so that it will no longer fit the socket properly. It has been proposed to provide a tool-holder of this class with an ejector device arranged to move longitudinally in the holder itself and to be projected more or 20 less into the drift-hole by the entered tool, so that the ejector instead of the tool will receive the impact of the drift and so avoid marring the tool. But this involves, among other objections, the following: That if the 25 ejector becomes badly burred by the drift it can only be removed from the holder with difficulty; and that the removable means to secure it against falling out when the tool is removed must necessarily be entered at 30 the periphery of the holder, where it is likely to work out and form a dangerous projection on the holder.

My invention contemplates providing a holder having a socket and a drift-receiving 35 hole transverse to and communicating with the socket and, in the socket, a removable container and, in the container, a drift-actuable ejector movable longitudinally of the socket and retained by the container 40 from falling out when the tool is removed.

In the best form of the invention one or all of the following features will also be embodied, to wit: That the container shall form also an auxiliary holder in which the 45 tool shank is actually received. That said container be formed in two sections separable to permit the removal of the ejector therefrom. That said container itself, when operatively contained in the holder socket 50 and adapted as an auxiliary holder, project into the drift-hole so that the container may be subjected to the ejecting action of the drift. And, finally, that the container

have means to afford a positive coupling between it and the tool. 55

In the drawing,

Fig. 1 is a view showing the improved holder in vertical section, with a tool and also a drift in operative position therein;

Fig. 2 is a side elevation, partly in section, of the container, with the ejector and a certain spring in position therein;

Fig. 3 is a sectional view on line 3-3, Fig. 2; and

Fig. 4 is a side elevation of the member 65 *g* of the container.

a is the holder of usual form, being say the tool-receiving portion of a drill spindle. *b* designates what is ordinarily the drill receiving socket of the holder and *c* 70 is the drift hole extending transversely into the holder and communicating with the socket. *d* is the drill or other tool having a tapered shank *d'* and a tang *d''* at the end thereof formed as usual in cross section substantially rectangular or otherwise with lateral facets. *e* is the drift. 75

Following the usual construction the socket *b* in the present example is shown tapered from the lower end of the holder upward. In it is fitted the aforementioned container which has an upward exterior taper conforming with that of the socket *b*. This container comprises two members 80 *f* and *g* constructed as follows: The lower member *f* has generally the form of a tapering sleeve formed near its upper end with a transverse wall *f'* having a rectangular hole *f''* therein of substantially the same form and size as the cross section of the 85 tang *d''*. The sleeve is of such thickness that when the tool shank *d'* is inserted therein the tang *d''* may enter the hole *f''* so that *d* and *f* will be positively locked together against independent rotation. From its upper end downwardly the sleeve *f* is internally threaded, as at *f'''*. The member *g* 90 has its basal portion *g'* exteriorly formed to continue the external contour of the member *f*, while its upper portion *g''* is shaped into a tang substantially rectangular in cross section. Member *g* has a bore *g''* extending therethrough and also a counterbore *g'''* formed therein from its lower end. 95

In addition, it has an externally threaded 100 depending extension *g''''* adapted to be 105

2
screwed into the upper threaded end of the member *f*.

The ejector is a pin *h* formed near one end with an integral collar *h'*. The ejector is arranged in the bore *g*³ with its collar *h'* in the counter bore *g*⁴ and when the members *f* and *g* are assembled as shown in Figs. 1 and 3 the collar rests on the wall *f'*, being of greater diameter than the width of the hole *f*². Preferably the counter bore contains a spiral spring *i* interposed between its upper end and the collar *h'*. In the stated position of the ejector its lower end protrudes into the opening *f*².

15 The container when arranged in the socket *b* of the holder has its tang *g*² projecting a little into the drift hole *c*. (In the present instance the container is assumed to be gripped by the holder so as to rotate therewith as an incident of the mere friction between the exterior of the container and the socket.) When the drill is inserted its tang is received in the hole *f*² and elevates the ejector from the position shown in Fig. 2 to that shown in Fig. 1. Whenever it is necessary to remove the tool the drift *e* is driven in sufficiently far to depress the ejector, which of course frees the tool from the container *f*. If, occasionally, the container is to be removed the drift may be driven in to a further extent than is necessary simply to actuate the ejector, its inclined surface *e'* being thus brought against the tang *g*². Since the section or member *g* fits the socket *b* the lateral thrust of the drift at this time is not borne by the screw joint *f*³ alone. In order that the more frequent removals of the tool may be effected without displacing the container, the tool is adapted, when in working position, to hold the ejector projecting further into the drift hole than the container.

Having thus fully described my invention, what I claim as new and desire to secure by Letters Patent is:—

1. In combination, a tool holder having a socket and a drift-hole arranged transversely of and communicating with the socket, a container in the socket, the socket and container having their respective interior and exterior surfaces tapered from the mouth of the socket in conformity with, and thereby gripping, each other and the container being divided transversely through its tapered portion into two sections separably screwed together, and an ejector arranged in and removable from the container on separating the said sections and movable longitudinally of the socket and adapted, when a tool is entered into the holder, to be displaced by the tool so as to project into the drift-hole.

2. In combination, a tool holder having a socket and a drift-hole arranged transversely of and communicating with the socket, a container including an upper section projecting into the drift-hole to be engaged directly by the drift and a lower section removably connected to the upper section, and an ejector movable in the upper section back and forth longitudinally of the socket and adapted to project upwardly into the drift-hole beyond the upper section, said upper section and the ejector having co-acting means to limit the relatively upward movement of the ejector, and said ejector being removable downwardly from the upper section when the lower section is detached from the latter but having its downward movement normally limited by the lower section.

In testimony whereof I affix my signature.

GIUSEPPE IVALDI.
